UNITED STATES PATENT OFFICE

165,589

AUTOMOBILE GRILLE BAR

Henry J. Keane, Grosse Pointe, Mich., assignor to Chrysler Corporation, Highland Park, Mich.,
a corporation of Delaware

Application August 7, 1951, Serial No. 16,192

Term of patent 7 years

(Cl. D14—6)

To all whom it may concern:

Be it known that I, Henry J. Keane, a citizen of the United States, residing in the city of Grosse Pointe, Wayne County, and State of Michigan, have invented a new, original, and ornamental Design for an Automobile Grille Bar, of which the following is a specification, reference being had to the accompanying drawing, forming part thereof, in which:

Fig. 1 is a front elevational view of an automobile grille bar, showing my new design;

Fig. 2 is a top plan view thereof;

Fig. 3 is a side elevational view thereof;

Figs. 4 and 5 are sectional views taken on the lines 4—4 and 5—5 of Fig. 3; and

Fig. 6 is a front elevational view thereof wherein the broken lines indicating an automobile are for illustrative purposes only.

The characteristic features of my design reside in the portions shown by means of full lines in the drawing.

I claim:

The ornamental design for an automobile grille bar, substantially as shown and described.

HENRY J. KEANE.
